UNITED STATES PATENT OFFICE.

MARTEN JOHN HOPKINS, OF ROCHESTER, NEW YORK.

MATERIAL-HANDLING APPARATUS.

Application filed November 21, 1921. Serial No. 516,609.

To all whom it may concern:

Be it known that I, MARTEN JOHN HOPKINS, a citizen of the United States, residing at Rochester, in the county of Monroe 5 and State of New York, have invented certain new and useful Improvements in Material-Handling Apparatus, of which the following is a specification.

My invention relates to apparatus particularly intended for handing building materials, whereby sand, gravel, stone, lime, cement, etc. may be conveniently assembled so as to be mixed together in proper proportions for use, and whereby these and other 15 materials such as brick, tile, etc. may be quickly and efficiently moved from one location to another or loaded onto vehicles for transportation.

My inventive idea, consisting of the details of construction of my improved apparatus and in its novel combinations and relative arrangement of parts, as will be hereinafter described in detail, is capable of embodiment in various mechanical structures, one of which is illustrated in the accompanying drawings, but it is to be understood that the structure shown is merely intended as a disclosure of my invention in its preferred form, and that its scope is as defined in the appended claims.

In the drawings, wherein like characters of reference denote corresponding parts in the different views—

Fig. 1 is a plan view showing the general assembly of the complete apparatus;

Fig. 2, a side elevation;

Fig. 3, a side elevation of the mixing bin;

Fig. 4, a detail plan of the shift line, anchor cable and adjusting means for the latter;

Fig. 5, a side elevation of the cable operating mechanism;

Fig. 6, a view at right angles to Fig. 5;

Fig. 7, a detail showing the manner of fastening the guide pulleys to the frame extension of the bin;

Fig. 8, a plan view of a suitable form of scraper for collecting materials;

Fig. 9, a side elevation of the scraper;

Fig. 10, a fragmentary front elevation of the hopper and its supports; and

Fig. 11, a cross section on the line A—A of Fig. 10.

Referring now to the drawings in detail, it will be observed that the apparatus includes a cable A, known as an anchor line, which is stretched between a pair of stakes a and is adapted to be drawn taut by screws a² threaded in the stakes a and including swivel eyes a' to which the ends of the line are attached.

Riding on the cable A is a pulley block c² which carries a pulley c' and an eye-hook c³, which latter has intermediately connected thereto a shift line B for moving the pulley block along the anchor line to any desired adjusted position, where it is held by securing the ends of the shift line to the stakes a.

The anchor and shift lines are located to one side of a pile or piles of material H to be handled, while substantially all of the remaining parts of the apparatus, consisting essentially of a hopper E, a bin V, and a conveyor R between the hopper and bin, are located on another side of the material. Means operating between the bin and anchor line for moving the material to the hopper completes the arrangement and consists essentially of a bucket or similar device preferably in the form of a drag scraper J as shown having connected to its rear end a line C and to its forward end a line D. The line C is carried rearwardly from the drag scraper towards the anchor line A and is trained over the pulley c', being then carried forward and trained over one or another of the sheaves v⁶ arranged in relative spaced relation along an arm v⁵ extending rearwardly from the bin V near one end of the latter, and is finally carried to a winding drum X of an operating mechanism carried by the bin. Similarly, the line D is carried forward from the drag scraper towards the bin V and is trained over one or another of a second series of sheaves v⁶ arranged in relative spaced relation along a second arm v⁵ extending rearwardly from the bin near

its opposite end, and is finally carried to a winding drum W of the operating mechanism mentioned.

With the foregoing arrangement it is apparent that when a pull is exerted on what may be termed the forward line D, and upon corresponding slackening of what may be termed the reverse line C, the drag scraper J will be moved forwardly over the pile of material H and during such movement will become filled with the material, while in a like manner, upon a pull being exerted on the reverse line C, and upon corresponding slackening of the forward line D, the drag scraper will be moved rearwardly over the material so as to be placed in position to be again drawn forwardly and filled.

The operating mechanism for effecting the aforementioned movements of the drag scraper may be of any approved type and placed in any desired location, but for the benefits of compactness and for convenience it is as previously stated desirably mounted on the bin by means of supports X³, W³ and Y' secured to bin frame members V⁴, and including reversing levers W', X' whereby both winding drums W and X may be caused to be rotated in either direction to respectively slacken and impart the necessary pull to the lines C and D. Rotation is imparted to the winding drums from a common drive shaft Y through a pinion on the drive shaft meshing with gears x² and w² on the respective drums, the shaft Y being driven in any desired manner as by means of a motor (not shown) mounted on the frame of the bin.

The hopper E is located between the arms v⁵ of the bin V and is adapted to receive material gathered by the drag scraper during forward movements of the latter, and to this end a baffle e' is provided which is inclined downwardly towards the material H for the purpose of facilitating forward movements of the scraper thereover prior to its contents being dumped into the hopper. A suitable frame e², e³ supports the hopper and a sliding door e⁴ is provided in one end of the same whereby its contents may be delivered to the conveyor R for elevation into the bin V, conveyor R being supported at a suitable incline by means of the braces r' between it and the bin, and being driven in any suitable manner as by a sprocket z² on drive shaft Y connected by a drive chain z with a sprocket z² on the conveyor, a clutch arrangement z' being provided on shaft y for controlling the conveyor's operation.

60 A partition v¹⁰ divides the bin V into two compartments, and a swinging trough r² at the upper end of the conveyor R provides means whereby material elevated by the conveyor may be directed into either

compartment. A suitably controlled delivery doorway v⁹ is provided for each compartment and the bin floor is inclined towards these doorways to facilitate delivery of material therethrough. Both doorways v⁹ open into a measuring hopper V' which is provided with a door v³ controlling its delivery opening. Thus, by manipulating the doors controlling the doorways v⁹, the contents of the bin compartments may be delivered in any desired proportions to the measuring hopper, from which delivery may be made to a vehicle, conveyor or other device as may be desired. Foldable platforms v² are provided on either side of the measuring hopper upon which an operator may stand in order to manipulate the delivery devices, and desirably the bin V is mounted on wheels G, F, whereby it and the mechanisms and devices carried thereby may be conveniently moved from one location to another.

From the foregoing it is apparent that by shifting the pulley block c² with its pulley c' along the anchor line A and by training the lines C and D over properly selected sheaves v⁶, the drag scraper J may be moved back and forth over the material H until the entire pile or any desired portion thereof has been delivered to the bin V, and by particular reference to Fig. 7 it will be observed that the sheaves v⁶ are flexibly connected to the arms v⁵ by means of eye-bolts v⁷ so that they may accommodate themselves to any variations in the lines C and D during manipulation of the latter.

From the foregoing description taken in connection with the accompanying drawings it is believed that the construction, operation and advantages of my improved apparatus will be clearly understood, but since various modification and desirable additions may be made in and to the same without departing from its spirit and within the range of ordinary mechanical skill, the present drawings with their related description are to be construed only as a disclosure of my invention in its preferred form, its scope being as defined by the terms of the appended claims.

I claim:—

1. Material handling apparatus including a drag scraper, a hopper, a pair of arms located one to either side of said hopper, cables for moving the scraper over a pile of material to thereby effect delivery of material to the hopper, and a plurality of spaced sheaves carried by each arm and selectively engageable by the operating cables whereby the drag scraper may be caused to traverse all portions of the pile of material.

2. Material handling apparatus including a drag scraper, a hopper, cables for moving the scraper over a pile of material to

effect delivery of the material to the hopper, for moving the scraper over a pile of material to effect delivery of the material to the hopper, and a plurality of relatively spaced sheaves secured to said member and selectively engageable by an operating cable whereby the scraper may be caused to traverse all portions of the pile of material.

3. Material handling apparatus including a drag scraper, a hopper, a member extending outward from said hopper, cables
